Hiram B. Nickerson

UNITED STATES PATENT OFFICE.

HIRAM B. NICKERSON, OF ORLEANS, MASSACHUSETTS.

MECHANICAL MUSICAL INSTRUMENT.

SPECIFICATION forming part of Letters Patent No. 249,200, dated November 8, 1881.

Application filed February 25, 1881. (No model.)

To all whom it may concern:

Be it known that I, HIRAM B. NICKERSON, of Orleans, in the county of Barnstable and State of Massachusetts, have invented a new and useful Improvement in Organettes, of which the following is a specification.

The nature of my invention consists in combining with the reed-board of an organette a set of recurved sounding pipes, the valve ends 10 of which open downward and are closed by a valve on the upper face of the valve-lever. The lever in its downward stroke actuates the bell-hammer.

In the drawings, Figure 1 is a vertical section, showing one set of my devices, consisting of the reed, its chamber, the recurved pipe, valve and lever, and bell and hammer. Fig. 2 shows, partly in elevation and partly in vertical section, my device for forming the vacuum-pipes.

Let A represent the upper part of the body of the organette, the bellows being placed below this part.

A' is the wind-chamber, at the top of which 25 I place the reed-board B, which has a set of reeds, one of which is shown at C, Fig. 1. Above and attached to the reed-board B is the part D, which is made in the form of a segment of a cylinder, as shown in Fig. 1, and is 30 provided with a set of channels or curved passages D'. (See Figs. 1 and 2.) The channels D', being covered by a thin veneer, E, form a

series of recurved pipes the mouths of which open downward.

H is a lever, having a valve, n, which closes 35 the end of the pipe D'. The end L of the lever H is shaped, as shown, so that it may pass upward through the holes in the music-paper and allow the valve n to open, and thus cause its reed to sound. That part of the paper that is 40 not perforated depresses the end L of the lever H. Thus closing the valve n stops its reed from sounding.

M and M' are two grooved rollers, which serve to keep the music-paper in place, and yet, 45 by their grooves, allowing free action of the levers H L. The levers H L are pivoted at K, and are provided with suitable springs, v.

N is a hammer pivoted at W and held up by the spring S. This hammer is operated by 50 the lower end of the lever H L, and made to strike the bell P when desired.

Having thus described my invention, what I desire to secure by Letters Patent is—

In an organette, the combination of the reed-board 55 B and the set of recurved pipes D with the valves n, levers H L, rollers M M', and music-sheet, all arranged to operate substantially as described and for the purpose set forth.

HIRAM B. NICKERSON.
